UNITED STATES PATENT OFFICE.

ULYSSES G. FULLER, OF HARTFORD, CONNECTICUT, ASSIGNOR TO UNDERWOOD TYPE WRITER COMPANY, OF NEW YORK, N. Y., A CORPORATION OF NEW JERSEY.

TYPE-WRITING MACHINE.

No. 921,605.

Specification of Letters Patent.

Patented May 11, 1909.

Application filed May 18, 1908. Serial No. 433,532.

To all whom it may concern:

Be it known that I, ULYSSES G. FULLER, a citizen of the United States, residing in Hartford, in the county of Hartford and 5 State of Connecticut, have invented certain new and useful Improvements in Type-Writing Machines, of which the following is a specification.

This invention relates to paper feeding devices of typewriting machines, and is in the nature of an improvement upon the mechanism disclosed in application No. 398,599, in which the platen is swung backwardly and forwardly by a crank, the first 10 movement to bring the platen to position to receive a bill, and the second movement to bring the bill to the printing point; said application relating particularly to means for securing blank spaces between the carbon entries of successive bills on a carbon sheet which is retained in the machine. In 15 said application, a crank is shown mounted on the platen frame, but is normally out of engagement with the platen, a single 20 swinging movement of the crank serving to rotate the platen. The crank is mounted loosely upon the platen axle, and a pawl or dog is pivoted upon the crank in position to engage a notched or toothed wheel, the 25 latter being fixed to the platen; a spring normally holding the pawl out of engagement with the notched wheel. A single 30 movement of the crank throws the pawl into engagement with the notched wheel, 35 such engagement being mechanically maintained until the crank is swung back to normal position, whereupon the spring throws the pawl or dog out of engagement with the toothed wheel, and also serves to 40 hold the crank in its normal position. In said application, the crank-operating dog is caused to skip one or more notches or teeth of the wheel during the initial portion of the initial stroke of the crank (or other 45 finger piece) and then to engage said wheel to turn it around, so that the platen is turned backwardly during the remainder of said stroke of the crank. The engagement of the dog with said wheel is also main- 50 tained during the entire return movement of the crank to normal position, so that the forward rotation of the platen effected by said wheel is greater than the backward rotation thereof. Thus the platen is caused 55 to turn backwardly a relatively short dis-

tance to receive a bill, and then forwardly a relatively long distance to bring the bill to printing position; and in this manner a space is left between the carbon records on the long record sheet, which is retained in 60 the machine during the writing of successive bills, as understood in this art. That is to say, the record sheet is turned back with the platen through a certain arc to the point where a new bill is introduced, and is then 65 turned forward with the platen through a greater arc, so that the record of the new bill is separated by a space on the record sheet from the record of the immediately preceding bill. 70

The object of the present invention is to simplify and improve the construction and operation of the latch or trip mechanism, which causes the dog or pawl to skip the teeth of the notched wheel to effect the spacing between the successive bills on the carbon sheet. I pivot upon the crank a pawl to engage the notched wheel, and I fix upon the pawl between its tooth and pivot a forward pin to fall into the recess in the rim 75 of the disk, that is, the rim which is perforated to form a rack for the crank stop. The pawl is pivoted between its ends upon said crank, and at the end opposite the tooth is provided with a second pin or projection, 80 to be engaged by a trip or latch which is pivoted upon the disk. During the latter part of the return movement of the crank, a spring upon the disk engages a notch provided between the pivot and tooth of the 85 pawl, and tends to throw the tooth of the pawl away from the wheel, but such vibration of the pawl is prevented by a second pin, the latter riding upon the outer face of the trip or latch. As the crank continues to 90 turn, the second pin escapes from the trip and permits the first or forward pin to spring into the recess in the fixed rim. The forward pin is of considerable length to engage the cam wall of said recess, while the 95 rear or second pin is short so as to clear entirely the rim or rack; and the trip projects from the face of said rim in position to be engaged by said second pin. Said recess is in the form of an arc, the forward wall 100 thereof serving to cam the pawl into engagement with the wheel, while the rear wall thereof serves as a stop for the return movement of the crank. 105

In the accompanying drawings, Figures 1, 110

2 and 3 are diagrams, the first showing the parts in normal position, the second showing the pawl engaged to the notched platen wheel, and the third showing the wheel as 5 having been turned by the pawl. Fig. 4 is a plan of a portion of the platen frame and platen of an Underwood front strike writing machine showing my improvements applied thereto. Fig. 5 is a sectional view to illustrate 10 the construction of the trip, etc. Fig. 6 is a face view of the disk upon which the trip is mounted and the spring to control the pawl. Fig. 7 illustrates the manner in which the pawl rides over the trip during 15 the return stroke of the crank. Fig. 8 is a view similar to Fig. 2, but showing the connection of the disk to the platen frame etc., the parts being shown in normal positions. Fig. 9 is a view similar to Fig. 8, 20 but showing the parts in the Fig. 3 position. Fig. 10 is a view similar to Fig. 9, but showing the forward stroke of the crank as arrested by the stop. Fig. 11 is a perspective view of a pawl-controlling spring. Fig. 12 is 25 a sectional plan of the platen-controlling devices.

The usual cylindrical platen 1 of an Underwood typewriting machine is fixed upon an axle 2 journaled in the ends 3 of a platen 30 frame, the end of the axle projecting through the platen frame end and having a finger-wheel 6 thereon by means of which the platen may be rotated forwardly or backwardly to an unlimited extent. The platen 35 is also provided with the usual line-spacing devices, of which a toothed line-space wheel 7 and a yielding detent 8 therefor are seen at Fig. 4. Said line-space wheel is advanced intermittently by a pawl 9 and lever 9^a. Upon 40 the end of the platen axle is secured a hub 10 of a wheel 14 having teeth or notches 15 agreeing in number with the teeth on the line-space wheel 7. The wheel 14 is rotatable by means of a pawl 16 pivoted between 45 its ends at 17 upon a crank 18, the tooth 19 of the pawl normally disengaged from the wheel, as at Figs. 1 and 8, to permit independent rotation of said wheel and the platen 1. The crank is mounted upon the 50 platen axle by means of a hub 20.

When the crank is swung forwardly from the Fig. 1 to the Fig. 2 position, a long pin 21 normally occupying an arched recess 22 in a fixed rim 23, engages the cam-shaped 55 forward wall 22^a of said recess, and forces the pawl tooth to engage a notch 15 of the wheel, Figs. 2 and 9. As the crank continues to swing forwardly, the pin 21 rides along the inner wall or edge of the rim 23, 60 whereby the pawl is locked to the wheel. The forward motion of the crank is arrested by a stop 24, which carries a pin 25, whereby the stop may be set to any of a series of holes 26 formed in the rim 23. The latter 65 is formed upon a disk 27 which is connected

by a link 28 to an ear 29 formed upon the platen frame end 3. Upon the return movement of the crank, a finger 30 projecting up from a spring 31, the end of the latter secured upon the disk by a screw 32, engages a recess 33 formed in the pawl between its pivot and its tooth, so as to tend to turn said pawl away from the wheel. The release of the pawl from the wheel is temporarily prevented by means of a trip 34, 70 which is engaged by a short pin 35 formed upon the opposite end of the pawl from the tooth 19. The pin 35 is short enough to clear the rim 23, and the trip 34 projects from the face of the rim to engage the pin 33. The latter rides upon the outer face of the trip, as at Fig. 7, and thereby holds the pawl temporarily in engagement with the tooth, so as to give an extra forward rotation to the platen during the final portion 75 of the return movement of the crank. As soon as the pin 35 escapes from the trip 34, the spring 31 snaps the pawl away from the wheel, and the forward pin or projection 21 flies up into the recess 22, Figs. 1 and 8, this 80 being its normal position. The crank is finally arrested in its return movement by engagement of the pin 21 with the rear wall of the recess 22, Fig. 1.

It will be understood that at the initial 95 portion of the forward stroke of the crank, the rear or second pin 35 turns the trip one side against the tension of a spring 36, Fig. 2. Said spring normally presses said strip against a stop 37. At Fig. 5, it will be seen 100 that the spring 36 is coiled about the pivot 37 of the trip, the latter preferably having a shoulder 38 flush with the face of the rim 23, and the spring being confined between said shoulder and the bottom of a recess or 105 bearing 39 formed in the rim to receive said shoulder. The trip is preferably in the form of a finger integral with the shoulder and extending along the rim 23. It will thus be seen that the forward stroke of the 110 platen is rendered longer than the backward stroke thereof, and hence that a blank space is left between the entries on the carbon sheet, which remains in the machine during the withdrawal of the old bill and 115 the insertion of the new one. The operator simply grasps the handle 40 provided upon the crank 18 and pulls the crank forward as far as it will go, and then after introducing a new bill pushes the crank back 120 to its starting point, whereupon the first line of writing may be begun upon the new bill without attention from the operator to the matter of properly separating the records on the record sheet.

It will be seen that the construction is much simplified and improved, and that it will prove reliable in use. It will be seen that the recess 22 is not closed at any point, and that the arrest of the crank 18 may be 130

conveniently effected by the engagement of the pin 21 with the rear wall of the recess, while the trip 34 extends backwardly from the recess with its free end adjacent thereto, 5 said trip being in the form of a tongue formed upon the shoulder 33 which is received in the pivot bearing in the rim. The forward pin or projection 21 has but two or three simple functions to perform, while the 10 trip-control of the pawl 16 is effected by a separate pin 35.

Having thus described my invention, I claim:

1. In a typewriting machine having a 15 platen frame, a revoluble platen, and a notched wheel to rotate therewith, the combination with a crank mounted to turn about the axis of the notched wheel, and a fixed member upon the platen frame provided 20 with an annular rim and having a rack for an adjustable stop to arrest the crank and also having a recess, of a pawl pivoted between its ends upon the crank and provided at its toothed end with a pin to engage the 25 inner side of the rim to hold the pawl in engagement with the wheel, said pawl provided upon its outer end with a second pin, a pivoted trip upon which the second pin rides during the retraction of the crank, and 30 a spring to turn the pawl away from the wheel and throw the first pin into the recess in the rim when the second pin escapes from said trip.

2. In a typewriting machine having a 35 platen frame, a revoluble platen, and a notched wheel to rotate therewith, the combination with a crank mounted to turn about the axis of the notched wheel, and a fixed member upon the platen frame provided 40 with an annular rim and having a rack for an adjustable stop to arrest the crank and also having a recess, of a pawl pivoted between its ends upon the crank and provided at its toothed end with a pin to engage the 45 inner side of the rim to hold the pawl in engagement with the wheel, said pawl provided upon its outer end with a second pin, a pivoted trip upon which the second pin rides during the retraction of the crank, and 50 a spring to turn the pawl away from the wheel and throw the first pin into the recess in the rim when the second pin escapes from said trip; said recess having a cam-edge to engage the first pin to throw the 55 pawl tooth into a notch in the wheel, and said trip yielding to the action of the second pin during the camming of the pawl.

3. In a typewriting machine having a 60 platen frame, a revoluble platen, and a notched wheel to rotate therewith, the combination with a crank mounted to turn about the axis of the notched wheel, and a fixed member upon the platen frame provided 65 with an annular rim and having a rack for an adjustable stop to arrest the crank and

also having a recess, of a pawl pivoted between its ends upon the crank and provided at its toothed end with a pin to engage the inner side of the rim to hold the pawl in engagement with the wheel, said pawl provided upon its outer end with a second pin, 70 a pivoted trip upon which the second pin rides during the retraction of the crank, and a spring to turn the pawl away from the wheel and throw the first pin into the recess in the rim when the second pin escapes from 75 said trip; said spring mounted upon said fixed member in the path of said pawl, to be engaged thereby during the return stroke of the crank, at a point between the pivot and 80 tooth of the pawl.

4. In a typewriting machine having a platen frame, a revoluble platen, and a notched wheel to rotate therewith, the combination with a crank mounted to turn about 85 the axis of the notched wheel, and a fixed member upon the platen frame provided with an annular rim and having a rack for an adjustable stop to arrest the crank and also having a recess, of a pawl pivoted between its ends upon the crank and provided 90 at its toothed end with a pin to engage the inner side of the rim to hold the pawl in engagement with the wheel, said pawl provided upon its outer end with a second pin, 95 a pivoted trip upon which the second pin rides during the retraction of the crank, and a spring to turn the pawl away from the wheel and throw the first pin into the recess in the rim when the second pin escapes 100 from said trip; said spring mounted upon said fixed member in the path of said pawl, to be engaged thereby during the return stroke of the crank, at a point between the pivot and tooth of the pawl, and the pawl 105 having a recess to receive said spring.

5. In a typewriting machine having a platen frame, a revoluble platen, and a notched wheel to rotate therewith, the combination with a crank mounted to turn about the axis of the notched wheel, and a fixed member upon the platen frame provided 110 with an annular rim and having a rack for an adjustable stop to arrest the crank and also having a recess, of a pawl pivoted between its ends upon the crank and provided at its toothed end with a pin to engage the inner side of the rim to hold the pawl in engagement with the wheel, said pawl provided upon its outer end with a second pin, 115 a pivoted trip upon which the second pin rides during the retraction of the crank, and a spring to turn the pawl away from the wheel and throw the first pin into the recess in the rim when the second pin escapes from said trip; said recess having a cam-edge to engage the first pin to throw the pawl tooth into a notch in the wheel, and said trip yielding to the action of the second pin during 120 the camming of the pawl; the first pin having 130

ing sufficient length to enter the recess in the rim, and the second pin sufficiently short to clear the rim; said trip projecting above the rim to engage the second pin.

- 5 6. In a typewriting machine having a platen frame, a revolute platen, and a notched wheel to rotate therewith, the combination with a crank mounted to turn about the axis of the notched wheel, and a pawl 70 pivoted upon said crank, of means to enable the crank to throw the pawl into engagement with said wheel and hold it there during the forward and backward movements of the crank, a spring having a support upon 75 15 the platen frame and arranged in the path of said pawl to engage the latter and throw it away from the wheel, said pawl provided between its pivot and tooth with a recess for said spring, and a trip to prevent the spring 80 20 temporarily from releasing the pawl at the return stroke of the crank.

7. In a typewriting machine, the combination with a platen, of a ratchet in connection therewith, a back-and-forth moving pawl 25 25 acting with the ratchet, means to disengage the pawl from the ratchet at a predetermined point in the movement of the pawl, a relatively fixed support, a trip pivoted thereon, means for limiting the motion of the trip 30 30 in one direction, a projection on the pawl adapted to ride past one side of the detent as the pawl is moving in one direction, temporarily to restrain the action of said means for disengaging the pawl, and to move past 35 the opposite side of the pawl when the ratchet is moving in the other direction, to permit the action of said means for disengaging the pawl, and a cam on the support to be engaged by a pin on the pawl when the 40 40 pawl is moving in the second named direction, to return the pawl to engagement with the ratchet.

8. In a typewriting machine, the combination with a platen, of a ratchet in connection 45 therewith, a back-and-forth moving pawl 45 acting with the ratchet, means to disengage the pawl from the ratchet at a predetermined point in the motion of the pawl, a relatively fixed support, a trip pivoted thereon, 50 a projection on the pawl, the projection moving past one side of the trip as the pawl is moving in one direction, temporarily to restrain the action of said means for disengaging the pawl, and past the opposite side 55 of the trip when the pawl is moving in the opposite direction to permit the action of said means for disengaging the pawl, a forward pin on the pawl, and a cam on the support, the forward pin engaging the cam to 60 60 return the pawl to engagement with the ratchet when the pawl is moving in the second direction after the action of said means for disengaging the pawl.

9. In a typewriting machine having a 65 platen frame, a revolute platen, and a

notched wheel to rotate therewith, the combination with a crank mounted to turn about the axis of the notched wheel, a pawl pivoted upon said crank and normally out of engagement with the wheel, and a fixed member 70 upon the platen frame and having a rim provided with a recess, of a pin projecting from said pawl into said recess to coöperate with the rear wall of the recess to form a stop for the crank, the forward wall of the recess being inclined to act upon said pin to force the pawl-tooth into engagement with the wheel, such engagement being maintained by the coaction of said pin with the inner wall or edge of said rim, a spring tending to release 80 said pawl from the notched wheel, a trip pivoted on said fixed member and extending backwardly from said recess, and having its free end adjacent to the recess, and a pin upon said pawl to ride upon said trip to prolong the engagement of the pawl with the wheel during the return stroke of the crank.

10. In a typewriting machine having a platen frame, a revolute platen, and a notched wheel to rotate therewith, the combination with a crank mounted to turn about the axis of the notched wheel, a pawl pivoted upon said crank and normally out of engagement with the wheel, and a fixed member 90 upon the platen frame and having a rim provided with a recess, of a pin projecting from said pawl into said recess to coöperate with the rear wall of the recess to form a stop for the crank, the forward wall of the recess being inclined to act upon said pin to force the pawl-tooth into engagement with the wheel, such engagement being maintained by the coaction of said pin with the inner wall or edge of said rim, a spring tending to release said pawl from the notched wheel, a trip pivoted on said fixed member and extending backwardly from said recess, and having its free end adjacent to the recess, and a pin upon said pawl to ride upon said trip to prolong the engagement of the pawl with the wheel during the return stroke of the crank. 95 100 105

11. In a typewriting machine having a platen frame, a revolute platen, and a notched wheel to rotate therewith, the combination with a crank mounted to turn about the axis of the notched wheel, a pawl pivoted upon said crank and normally out of engagement with the wheel, and a fixed member 115 upon the platen frame and having a rim provided with a recess, of a pin projecting from said pawl into said recess to coöperate with the rear wall of the recess to form a stop for the crank, the forward wall of the recess being inclined to act upon said pin to force the pawl-tooth into engagement with the wheel, such engagement being maintained by the coaction of said pin 120 125 130

- with the inner wall or edge of said rim, a spring tending to release said pawl from the notched wheel, a trip pivoted on said fixed member and extending backwardly 5 from said recess, and having its free end adjacent to the recess, and a pin upon said pawl to ride upon said trip to prolong the engagement of the pawl with the wheel during the return stroke of the crank; said trip 10 overlying the face of the rim, and said trip pin being short enough to clear the rim; said trip being in the form of a tongue formed upon a shoulder which is received in a recess or pivot-bearing in the rim, and said 15 pawl-releasing spring being mounted upon said fixed member, and having a part to engage the trip between its pivot and its tooth.
12. In a typewriting machine having a 20 platen frame, a revoluble platen and a notched wheel to rotate therewith, the combination with a crank mounted to turn about the axis of the notched wheel and a member fixed upon the platen frame and provided 25 with an annular rim, said rim having a recess, of a pawl pivoted upon the crank and having a pin to enter said recess to coöperate with the latter to cam the pawl into engagement with the wheel, a trip and a 30
- separate pin or projection up said pawl to 35 engage said trip to coöperate with the latter to prolong the wheel-engaging movement of the pawl at the final portion of the return stroke of the crank.
13. In a typewriting machine having a 35 platen frame, a revoluble platen and a notched wheel to rotate therewith, the combination with a crank mounted to turn about the axis of the notched wheel and a member fixed upon the platen frame and provided 40 with an annular rim, said rim having a recess, of a pawl pivoted upon the crank and having a pin to enter said recess to coöperate with the latter to cam the pawl into engagement with the wheel, a trip and a 45 separate pin or projection upon said pawl to engage said trip to coöperate with the latter to prolong the wheel-engaging movement of the pawl at the final portion of the return stroke of the crank; said trip being 50 located on said rim at a different point from said recess, and the first pin coöoperating with the rear wall of the recess to arrest the crank in its return movement.

ULYSSES G. FULLER.
